ATELIERS OTIS PIFRE, OF PARIS, FRANCE.

AERIAL ROPEWAY FOR TRANSPORT AND HAULAGE.

1,404,840.

Specification of Letters Patent. Patented Jan. 31, 1922.

Application filed July 25, 1919. Serial No. 313,397.

To all whom it may concern:

Be it known that I, ERNEST ALPHONSE DEFUNGS, a citizen of the Republic of Switzerland, of Paris, France, have invented 5 Improvements in Aerial Ropeways for Transport and Haulage, of which the following is a full, clear, and exact description.

A system of transport or haulage on a fixed cable usually comprises a cable, which 10 may consist of a single rope or of a combination of several cables operating in parallel, resting on a number of intermediate supports arranged at intervals, the extremities of the cable system being firmly secured by 15 anchoring.

Since the sag of the cable must be reduced to the minimum, it is necessary to give a powerful initial tension, which usually acts solely on the anchors, the intermediate supports being subjected, for the most part, to 20 corresponding stresses which are practically equal on both sides of each support.

Apart from this initial tension, the cable has to support various stresses. viz.—the 25 weight of the cable, the weight of the carriage or tractor, (when this is carried by the cable,) and the reaction of the haulage rope in the case of hauling or towing.

These stresses resolve themselves into two 30 components; the one tangential to the cable at the mean point of application of the carriage or of the haulage attachment, and the other in a plane at right angles to the cable at the same point.

The longitudinal component only puts a 35 comparatively light strain on the intermediate supports, but this is not the case with the vertical component which, by reason of the very slight sag of the cable, transmits very considerable strains to said supports and in order to take up these strains it has, hitherto, been found necessary to employ supports of great strength which are 40 consequently expensive.

The object of the present invention is to 45 reduce the stresses on the supports to a minimum, so as to lessen the importance and cost of these supports.

The invention consists essentially in a combination of two cables whereof the one, 50 tightly stretched, takes up the horizontal stresses while the other, lightly stretched and deeply sagged, supports the whole of the transverse stresses.

By way of example, the accompanying

drawing illustrates diagrammatically, various methods of carrying out the invention in practice. In the drawing, Figure 1 represents an elevation of a section of the aerial ropeway system; Figure 2 an end view 60 thereof and Figure 3 a similar view of a modification; Figure 4 shows the application of the new system applied to towing on a canal, Figures 5 and 6 being respectively a side elevation and plan of this latter arrangement. 65

As can be seen from the drawing (Figures 1 and 2) the new aerial ropeway system comprises intermediate supports *a*, arranged at intervals all along the line of route, and carrying brackets or arms *b*, which may be fixed or articulated. 70

These brackets support two cables *c* and *d*, *c* being lightly stretched and therefore sagging deeply, whilst *d* is under powerful tension and has but little sag. 75

The cable *c* supports a carriage or tractor *e* driven by any suitable motor and provided with means of any kind for ensuring adhesion. 80

The cable *c* is stretched by the weight of the tractor, but the resulting longitudinal stresses are supported by the other cable *d* in the spans adjacent to the one under consideration, because the two cables are attached to the same brackets. 85

In Figure 3 the carriage *e* is operated by haulage or towing by means of an attached rope *f*, the oblique pull of which draws the carriage out of the plane of suspension. 90 Owing, however, to the large sag of the cable, only small stresses are transmitted to the supports.

In the arrangement shown in Figs. 4 to 6, instead of having a carriage *e*, carried by the cable *c*, a tractor *t* runs on the ground, or on a suitable track; this tractor grips on the cable *d* to go forward. 95

The tractor tows a barge *g* by means of a rope *f* secured to a traveller or auxiliary carriage *h* which runs freely on the sagging cable *c*, to which it transmits the greater portion of the transverse stress due to the obliquity of the towing pull. That portion of the rope which is between the traveller *h* and the tractor *t* may be of sufficient length to reduce the transverse stress on the tractor to a minimum. 100

The pull exerted by the carrier on the cable *c* sets up stresses, in the arms *b*, which 110

tend to subject the cable *d* to a supplementary tension. To facilitate the distribution of the tensions over the whole length of this cable, the arms *b* may be articulated on the supports. This arrangement has also the advantage of lessening the strain on the system when in repose, the cable *c* automatically taking up, under the action of its own weight, the lowest position compatible with the arrangement of the arms *b*.

It will be understood that the schemes just detailed are only a few of the methods of carrying out the invention, which may be modified in various ways in practical application. Thus, without departing from the spirit of the invention, either of the cables may be used for the propulsion of the tractor; the brackets may be dispensed with by attaching the cables direct to the supports; the sagging cable may be subjected to a momentary pull, by any suitable means, during the passage of the tractor or traveller, so as to increase the sag in the corresponding portions of the cable and thereby lessen longitudinal stresses, the sag becoming so great that the cable rests on the ground; the rigidity of the taut cable may be increased by providing a catenary suspension; one or other of the cables may be replaced

by a chain or other equivalent device, with a view to improving the adherence; one or other of the cables may be replaced by a plurality of cables; an endless rope may be employed for the transmission of motive power, such rope being independent of the fixed cables comprised in the system.

Moreover, any of the detail devices may be modified in any case to suit the particular method of application.

Claim—

In an aerial ropeway for transport and haulage, supports placed on a different line from the path of the body hauled, a cable which is stretched taut and connecting said supports, another cable under light tension, the two cables being fixed at the same points on the supports, the traveller being carried by this cable under light tension,—a tractor running on the ground, in the plane of the taut cable, a rope fixed to the tractor, passing on the traveller, and fixed to the body moved, this rope making a very small angle relatively to the taut cable.

The foregoing specification of my improvements in aerial ropeways for transport and haulage, signed by me, this twenty-third day of June, 1919.

ERNEST ALPHONSE DERUNGS.
